(57) **CLAIM**

The ornamental design for an accessory tool holder for a hand tool, as shown and described.

DESCRIPTION

FIG. 1 is a perspective view of an accessory tool holder for a hand tool according to our new design;

FIG. 2 is a top plan view thereof;

FIG. 3 is a bottom plan view thereto;

FIG. 4 is a left side elevation view thereof;

FIG. 5 is a right side elevation view thereof;

FIG. 6 is a front elevation view thereof;

FIG. 7 is a rear elevation view thereof;

FIG. 8 is a perspective view thereof, shown in the environment of a hand tool; and,

FIG. 9 is a top plan view thereof, shown in the environment of a hand tool.

The broken lines immediately adjacent the shaded areas represent bounds of the claimed design and environment while all other broken lines are directed to environment and are for illustrative purposes only. The broken lines form no part of the claimed design.
